(57) **CLAIM**

We claim the ornamental design for an arm elevation sling, as shown and described.

DESCRIPTION

FIG. 1 is a perspective view of an arm elevation sling showing our new design for a right arm;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The corresponding views of our arm elevation sling for a left arm are mirror images of those shown.
